UNITED STATES PATENT OFFICE.

ERNEST B. BEAUMONT, OF ANN ARBOR, MICHIGAN.

IMPROVEMENT IN DOMESTIC BOILERS.

Specification forming part of Letters Patent No. **150,222**, dated April 28, 1874; application filed June 14, 1873.

To all whom it may concern:

Be it known that I, E. B. BEAUMONT, of Ann Arbor, Washtenaw county, in the State of Michigan, have invented a new and Improved Domestic Boiler; and I do hereby declare that the following is a full, clear, and exact description of the same, reference being had to the accompanying drawing forming part of this specification.

The invention will first be fully described, and then clearly pointed out in the claim.

Figure 1 is a sectional elevation; Fig. 2, partly a sectional and partly a side elevation.

A is the water-holding vessel; B, the fuel-pan; C, the base, and D the handle for lifting

the apparatus. The handle D is hinged to the vessel A at F, so as to swing upon the top and avoid being heated, and has plates or bars G to brace the handle, and to prevent the spread thereof.

Having thus described my invention, what I claim as new, and desire to secure by Letters Patent, is—

The top hinged boiler-handle D, provided with bars G, as and for the purpose described.

ERNEST B. BEAUMONT.
